UNITED STATES PATENT OFFICE.

WILLIAM W. TAYLOR, OF MONTCLAIR, NEW JERSEY.

METALLIC BUILDING.

1,155,969.

Specification of Letters Patent.

Patented Oct. 5, 1915.

Original application filed March 14, 1913, Serial No. 754,216. Divided and application filed November 12, 1913, Serial No. 800,493. Divided and this application filed May 19, 1915. Serial No. 29,105.

To all whom it may concern:

Be it known that I, WILLIAM W. TAYLOR, a citizen of the United States, and a resident of Montclair, in the county of Essex and State of New Jersey, have invented a new and Improved Metallic Building, of which the following is a full, clear, and exact description.

The present invention is a division of application for Letters Patent filed by me November 12, 1913, Serial No. 800,493, which was itself a division of an application filed by me March 14, 1913, Serial No. 754,216.

The present invention relates more particularly to the ridge of the roof and to the co-acting roof plates.

Reference is had to the accompanying drawings forming part of this specification, in which similar characters of reference indicate corresponding parts in all the views, and in which:

Figure 1 is a transverse vertical section showing a portion of a building employing my invention; and Fig. 2 is a detail in vertical cross-section on the line 2—2 of Fig. 1.

The roof is employed in connection with suitable metallic side walls 10, which, in the example shown, have inner and outer ribs 11, 12. On the upper end of the side plate 30 is a roof supporting plate 13 which receives the roof plates 14, bolts or screws 13^a and nuts 13^b being shown as a means for uniting the roof plates to the supporting elements 13.

My improved roof ridge, designated generally by the numeral 15, has a core 15^a in the form of an angle bar in general of inverted V-shape in cross-section. Around the said core is bent a sheet of plate metal which follows approximately the general angular formation of the core 15^a at the underside and the upper side and is extended outwardly. Thus at the sides of the core 15^a the sheet metal covering is so formed as to present lateral approximately horizontal wings or flanges 15^b of double thickness. From the wings 15^b the opposite sides of the covering plate are brought against the top of the core 15^a and then continued upwardly in close relation, to constitute a vertical rib rising from the base. The terminal of the sheet at one side of the rib is bent downwardly at the outside of the terminal edge of the sheet at the opposite side of the rib. The rib of the ridge thus presents three

thicknesses of sheet material, as indicated by the characters 15^c, 15^d, and 15^e. The several thicknesses of the rib may be united together by bolts 26, and nuts 27.

The roofing plates or sheets 14 are formed with upper and lower ribs 14^a, 14^b, at the joints thereof, in the formation of which ribs one side edge of a plate is first bent upwardly as at 14^c and return bent as at 14^d, said return bend being continued across the plane of the roofing plate to the underside and return bent on itself as at 14^e to form the inner rib 14^b. The described ribs at the upper side are received in a channel presented by the opposite edge of the adjacent plate, the channel being produced by bending the edge of the plate first upwardly, as at 14^c, and then downwardly as at 14^e, the said bends being spaced apart to receive the mating bends 14^c, 14^d on the opposite plate.

A cover plate 16 is placed over the ridge and inclines downwardly from the peak of the roof over the upper ends of the roofing plates 14. At the lower edges of the cover plate the latter is bent downwardly at substantially a right angle as at 16^a to contact with the outer surface of the roofing sheets, and again bent at approximately right angles to provide securing feet 16^b. Bolts 25 and nuts 25^a or equivalent means may be employed to secure the said feet 16^b to the roofing plates 14.

It will thus be seen that since the body of the cover 16 rests on the outer ribs 14^a, a space is produced between the cover and the bodies of the roofing plates 14, and this space is open at the upper end between the roofing plates and the ridge 15 and communicates with spaces between the ribs 16^b at the underside of the roofing plates. I form holes 16^c in the downturned portion 16^a of the cover 16. In this way there will be a circulation of air upwardly from the interior of the building between the under-ribs 16^b, around the upper ends of the roofing plates and downward and outward beneath the cover 16 through the holes 16^c.

Having thus described my invention, what I claim as new and desire to secure by Letters Patent, is:

1. In a metallic building, side walls, roofing plates supported on said walls, and a ridge at the upper ends of the roofing plates, the said roofing plates terminating at the upper ends adjacent to the opposite sides

of the ridge, and said ridge consisting of a core in the form of an angle bar of inverted V-shape, and a plate of sheet metal covering the core, said sheet metal covering 5 extending across the underside of the core and outwardly at the sides of the latter in the form of wings, the sides of said plate extending from the wings inwardly over the upper side of the core and extending 10 upwardly in close relation in the form of a vertical rib, the terminal of the plate at one side being returned over the terminal edge of the other side.

2. In a metallic building, side walls, roofing plates on said side walls, a ridge, said roofing plates terminating at their upper 15 ends adjacent to the opposite sides of the ridge and inclined to each other, and a cover plate extending over the ridge and over the upper ends of the roofing plates, the said roofing plates having ribs at the upper side and at the underside thereof and the cover plate extending downwardly at the side edges between the said upper ribs of the roofing plates, and being secured to the 20 said plates.

3. In a metallic building, side walls, roofing plates on said side walls, a ridge, said roofing plates terminating at their upper 25 ends adjacent to the opposite sides of the ridge and inclined to each other, a cover plate extending over the ridge and over the

upper ends of the roofing plates, the said roofing plates having ribs at the upper side and at the underside thereof and the cover 35 plate extending downwardly at the side edges between the said upper ribs of the roofing plates, and being secured to the said plates, the said downwardly extending edges of the cover plate having ventilating 40 openings, the spaces between the upper and lower ribs of the roof plates being in communication with each other, and the said spaces at the underside of the roof plates being open for the escape of air from beneath the roof.

4. In a metallic building, roofing plates, means supporting said roofing plates, and a ridge between the roofing plates, said ridge comprising a base having a core in the form 45 of an inverted V-shaped bar and a sheet metal covering, said covering presenting wings at the sides of the said core and being formed into a vertical rib above the core, the rib presenting a plurality of thicknesses 50 lying against each other.

In testimony whereof I have subscribed my name to this specification in the presence of two subscribing witnesses.

WILLIAM W. TAYLOR.
